CABLE CONTACT

Edwin R. Goldfield, University Heights, Ohio, assignor to Picker X-Ray Corporation, Waite Manufacturing Division, Inc., Cleveland, Ohio, a corporation of Ohio

Application July 12, 1940, Serial No. 345,080

2 Claims. (Cl. 173—324)

This invention relates to improvements in electrical cable connectors and particularly to improvements in means for connecting heavy electrical cables to high voltage equipment such as X-ray tubes and the like.

Electrical connections to high voltage equipment such as X-ray tubes include very heavy cables sometimes almost an inch in diameter carrying several conductors which are very heavily insulated because of the high voltages carried. For instance it is common in connections to X-ray tubes to use a cable carrying three conductors, one for the tube anode or cathode, one for the filament and one for the return line. These cables are connected to tube equipment which must necessarily be manipulated in the ordinary course of operations. Such manipulation requires movement of the connecting cables which, because of their heavy character, are not easily distorted. It is very desirable therefore to provide cable connectors permitting a twisting or rotation of the cables in their sockets without disturbing the electrical connections. It is also important that such contacts be adapted to carry the high voltages used in a safe manner and particularly to prevent spark-over and corona effects when the high voltages are used in humid atmosphere or at high altitudes.

One of the objects of the present invention is to provide a novel means for connecting electric cables comprising coacting sets of concentrically arranged interfitting contact members permitting relative rotation between the movable contact members connected with the electrical cable and the fixed contact members on the X-ray tube equipment.

Another object of the present invention is to provide a very rugged connection of electrical cables with high voltage equipment permitting a twisting of the cables and at the same time rendering any spark-over practically impossible and housing the parts in such a manner that they are sufficiently rugged to stand much abuse even to the extent of being dragged through mud and water as is sometimes necessary with army equipment or other emergency use of X-ray apparatus.

Other objects and advantages of the present invention will be apparent from the accompanying specification and drawing and the essential features will be set forth in the claims.

In the drawing, Fig. 1 is an elevational view of my improved cable connector; Fig. 2 is an enlarged fragmental sectional view of the male member of the connector taken along the line 2—2 of Fig. 3; Fig. 3 is a bottom plan view of the connector member of Fig. 2; Fig. 4 is an enlarged fragmental sectional view of the female connector member of Fig. 1 taken approximately along the line 4—4 of Fig. 5; Fig. 5 is a transverse sec-

tional view taken along the line 5—5 of Fig. 4; while Fig. 6 is a sectional view of one of the contact members of Figs. 2 and 3.

In the drawing it will be understood that the cable 10 is a cable of the usual character found in X-ray equipment carrying three electrical conductors 11, 12 and 13, one of which is adapted to carry the tube current, one for the filament current and one for the return line. Such currents are of the order of 25,000 peak volts or higher. These same currents are carried on to the equipment served by the connections 14, 15 and 16, leaving the other end of the device here disclosed. It will be understood that the conductors extending beyond the points 14, 15 and 16 are generally oil immersed and the design of my improved connector takes this feature into account.

My novel connector device includes an inner cylindrical sleeve 17 and an outer cylindrical sleeve 18 having an overall length in the present embodiment of from four to six inches for a purpose which will be later described. The clearance between the outside diameter of sleeve 17 and the inside diameter of sleeve 18 is just sufficient to permit a sliding fit of one sleeve within the other. This keeps the air gap between the sleeves at a minimum.

Referring now to the construction of the inner sleeve 17, it comprises a hollow cylinder 17a of a rigid insulating material such as "Bakelite" or the like provided with a manipulating flange 17b at the cable end thereof. This flange 17b is a part of the grounded sheath with which the high tension cables are usually provided. The cable 10 or its associated electrical conductors enter at one end of the cylinder 17a and pass along substantially the entire length thereof to the free end where the electrical conductors are secured to a set of contact members indicated generally at 19. The contact members are secured to a heavy sheet of insulating material 20 which closes the end of the cylinder 17a and all of the free space within the cylinder 17a and surrounding the cable and its conductors indicated generally at 21 is filled with a plastic insulating material which flows readily when heated and stiffens upon cooling. This completely seals and fills the entire space within the cylinder 17a up to the member 20. A spring strip of corrugated metal 22 engages in recesses 23 on the inner face of cylinder 17a so as to serve to position the member 20.

Referring now to the set of contact members indicated generally at 19, this comprises annular substantially rigid contact members 19a, 19b and 19c concentrically arranged. Each of the contact members has portions passing through the member 20 and bent down on the inside thereof so as to firmly hold the contact members in place. The conductors 11, 12 and 13 are soldered to their

associated contact members so as to form permanent connections. The contact members have longitudinally extending slots as indicated at 24 so as to provide a slight yielding effect the better to frictionally engage the coating set of contacts carried by the sleeve 18. A detailed arrangement of the contact member 19b is shown in Fig. 6 where the longitudinally extending slot 24 is extended in T-form as indicated at 24a so as to give greater flexibility at the free ends of the 10 contact member.

The sleeve 18 is threaded as indicated at 18a for attachment to an X-ray tube or to an oil immersion tank carrying the associated equipment. The sleeve also has provided integrally 15 therewith a transversely extending wall 18b which carries centrally thereof a set of contacts indicated generally at 25.

The set of contacts 25 comprises three substantially annular contact members 25a, 25b and 25c concentrically arranged preferably in such a manner that they lie radially outside of the respective contact members in the set 19. Referring to the detailed arrangement of Figs. 4 and 5, the member 25c has a truncated conical surface 26 which engages a complementary surface of the wall 18b, these surfaces being tightly pulled together by a nut 27 threaded on the member 26, thus holding in place the connector member 15, a washer 28 and a gasket 29. A spacer 30 of insulating material having truncated conical shape spaces the members 25c and 25b. The member 25b is held assembled by a nut 31 which holds in place the connector member 16 and a sheet of insulating material 32. A spacer 33 of insulating material having truncated conical form separates the contact members 25b and 25a. The member 25a has a threaded stem 34 to the lower end of which is attached a nut 35 which secures in place the connector member 14 and a sheet of insulating material 36. It will be noted that the set of contact members assembled at 25 together with the wall 18b seals one end of the shell 18 against liquid leakage from the oil immersion compartment generally connected to the threads 18a.

When the parts are assembled as shown in Fig. 1, the contact members of the set 19 frictionally engage and overlap the contact members of the set 25 with the corresponding members of the set 25 lying radially outward of the members of the set 19. The cylinder 17a then provides a skirt 17c at its inner or free end which engages tightly against the wall 18b, thus overlapping and housing both sets of contacts and practically preventing any spark-over from them. In any case spark-over travelling from the set of contacts 25 toward the cable 10 would have to travel downwardly as viewed in Fig. 1 for the exposed length of contact member 25c and then upwardly along the outside of the cylinder 17a. Thus an overlapping of the parts 17c and 25c, by for instance three-eighths of an inch, will compel any spark-over to traverse a path of more than three-quarters of an inch, at the same time relative rotation of the contacts 19 and 25 may occur freely without any strains on the cable 10.

The arrangement of the concentric annular contacts 19 and 25 provides a much greater area of coating contacting surfaces than is found in the customary interengaging prongs of the prior art.

What I claim is:

1. An electric cable connector comprising inner and outer sleeves of rigid insulating material adapted to have a sliding fit one within the other, the clearance between the outside diameter of said inner sleeve and the inside diameter of said outer sleeve being just sufficient to permit sliding movement between the sleeves, said sleeves having a length of approximately four or five inches, a set of relatively fixed contact members, said outer sleeve having a transverse wall near one end supporting said set of contact members centrally of said sleeve with the contact members extending into the sleeve from said wall, said wall and set and mounting therefor closing and sealing said sleeve end, electric cable conductors entering at one end of said inner sleeve and extending through substantially its entire length to the other or free end thereof, a second set of contact members connected to said cable conductors, plastic insulating material sealing said conductors and said second set of contact members within said inner sleeve, each of said sets of contact members comprising a plurality of concentric members insulated from members in the same set, said sets interfitting and overlapping when said sets are in engagement with the members of the relatively fixed set respectively radially outside the members of the second set, and the free end of said inner sleeve surrounding the outermost contact member of said fixed set and forming a continuous skirt engaging said wall when said sets of contact members are in operative engagement.

2. An electric cable connector comprising male and female members of rigid insulating material, said members being of interfitting cylindrical form with just sufficient clearance between the outside diameter of the male member and the inside diameter of the female member to permit axial sliding movement between them, two frictionally engageable sets of concentrically arranged contacts, the contacts of each set being electrically insulated from each other, said sets being positioned rigidly one on each of said members in position to be engaged only when said members are in interfitting engagement with one member fully within the other, whereby one of said sets of contacts is at the inner end of said male member, an electrical cable integrally connected with the outer end of said male member and having an outer sheath of low potential, said cable having internally thereof a plurality of conductors adapted to carry a current of high potential of the order of 25,000 peak volts, said conductors being integrally joined respectively with the contacts of that set positioned at the inner end of said male member, and said male member being of such a length that there is at least three inches between the set of contacts at the inner end of said male member and the nearest point of the outer sheath of said cable at the outer end of said male member, whereby said cable and male member may be rotated relative to the set of contacts on said female member and when said sets of contacts are engaged the spark-over or corona effects must travel at least three inches from said contacts through the limited clearance space between said members to reach the nearest exposed point on said cable.

EDWIN R. GOLDFIELD.
